UNITED STATES PATENT OFFICE

2,573,687

SPRINKLER

Myron R. Bröck, College Park, Md.

Application September 7, 1948, Serial No. 48,005

6 Claims. (Cl. 299—69)

1

The present invention relates to sprinkling apparatus and more particularly to apparatus for incorporating fluid or fluid soluble chemicals such as fertilizer, insect or weed killer or the like in the fluid spray of the sprinkler.

The use of fluid or water soluble or water suspended fertilizers, weed killers, insect-killers and the like have gone into widespread use but the application of these materials presents certain practical difficulties. Heretofore these materials have been applied by separate pumps or the like and pumps of any substantial capacity become so heavy and involve so many other difficulties that spraying even small yards is difficult and unpleasant. In addition many of the fluids and soluble or suspendable materials tend to settle out and clog pumps and other spraying equipment so that it is necessary to keep the material stirred during use and to wash the pump or sprayer after each use.

Incorporating these materials in the water used for ordinary sprinkling or irrigating would simplify the task of applying these materials, would increase the use of these materials and would enable householders and others to have better lawns and gardens with a minimum of unpleasant labor.

One of the objects of the present invention is to provide a simple and efficient apparatus for incorporating fluid spray materials the stream of a sprinkler.

Another object is to provide apparatus for mixing fluid spray materials with the stream of a sprinkler and keeping the spray materials agitated during use.

A further object is to provide apparatus for introducing fluid spray materials into the stream of a sprinkler in which the spray materials cannot settle in the pipes of the sprinkler.

These and other objects and advantages reside in certain novel features of construction, arrangement and combination of parts as will hereinafter be more fully set forth and pointed out in the appended claims.

Referring to the drawing:

Figure 1 is a vertical section of one embodiment of my invention with parts shown in elevation.

Figure 2 is an enlarged fragmentary vertical section similar to Figure 1 showing the aspirator.

Figure 3 is a fragmentary vertical section of a modification of my invention.

Figure 4 is an elevation of a nozzle with parts broken away to show internal structure.

In the drawing I have illustrated my invention

2

as applied to a rotary head lawn sprinkler having a base 10 through which a conduit 11 extends from the edge to the center. A suitable fitting 12 is secured to the base 10 adjacent the edge for connection with a hose or pipe 13.

A pipe 14 connected to the conduit 11 extends vertically upward from the center of the base 10 and a tubular spindle 15 is threaded on the top of the pipe 14. The spindle 15 has a projecting shoulder 16 and a cap 17 extends downwardly over the spindle 15 and has an inward shoulder 18 which rests on the top of the shoulder 16. The lower end of the cap 17 is threaded to receive a sleeve 19 which engages the lower surface of the shoulder 16. The clearances between shoulders 16 and 18, sleeve 19 and shoulder 16 and sleeve 19 and spindle 15 are such that the cap 17 and sleeve 19 are freely rotatable on the spindle 15 but are not removable therefrom without unscrewing the sleeve 19 from the cap 17.

A hollow container 25 is fixed to the cap 17, preferably by soldering, welding or the like so that there is a fluid-tight joint between the container 25 and the cap 17.

The cap 17 is formed with a space or chamber 26 above the open upper end of the spindle 15 and openings 27 extend laterally through the cap 17 into the chamber 26. My improved discharge and mixing device is secured in each opening 26 and since these devices are identical, only one will be described.

Each discharge and mixing device consists of a discharge pipe 30 threaded into the cap 17 in communication with an opening 27. Each pipe 30 extends radially outward from the cap 17 and an aspirator 31 is secured at the outer end of each pipe 30 by a suitable fitting 32. The end of the aspirator 31 extends through an opening 33 in the wall of the container 25 and is provided with a nozzle 34. The nozzle 34 is preferably angularly adjustable in any well known manner and may have the usual adjustable stop 35 for controlling the character of the stream.

The aspirator 31 has a suction intake 36 to which a suction pipe 37 is secured by a suitable fitting 38. For purposes hereinafter described, the pipe 37 is provided with a ball check 39 and a pet cock 40. The pipe 37 extends downward toward the bottom and outside wall of the container 25 and the end of the pipe 37 may be covered by a screen or mesh 41 to prevent large particles from entering the pipe.

The container 25 is provided with a lid or cover 45 having a handle 46 secured thereto by screws 45 or bolts 47. A suitable air vent 48 is formed in

the lid or cover 45 and I prefer to control the flow of air through this vent 48 by a suitable pet cock 49.

In operation, the fluid to be incorporated in the water spray is placed in the container 25. This fluid may be a fertilizer, weed killer, bug killer or other spray material and the term "fluid" includes fluid materials and solutions or suspensions of solid materials in fluid. Many fertilizers and weed or insect sprays are water soluble and with such materials a strong water solution would be placed in the container 25.

The nozzles 34 are set at an angle so that the stream issuing from one or more of the nozzles has a tangential component sufficient to rotate the container 25 and cap 17 on the spindle 15. The passage of water through the aspirator 31, draws fluid from the container 25 up through the pipe 37 and the fluid mixes with the water so that plants may be sprayed with proper chemicals at the same time they are watered. As the container 25 rotates the fluid tends to move outward toward the wall of the container 25 by centrifugal force and the intake end of the pipe 37 is preferably positioned so that this centrifugal force tends to aid the aspirator in forcing fluid up the pipe 37 toward the aspirator.

The relative proportion of fluid to water in the spray may be controlled by the pet cock 40 which limits the amount of fluid passing through the pipe 37 to the aspirator 31. The relative proportion of fluid to water in the spray may also be controlled by the pet cock 49 which limits the entry of air into the container 25. Control by this pet cock 49 is not as effective or critical as control by the pet cock 40 but pet cock 49 can be used for rough control or to stop the flow of fluid through the pipe 37.

When the pet cock 49 is partially or wholly closed, withdrawal of fluid from the container 25 by the aspirator 31 causes a partial vacuum in the container 25 and the ball check 39 prevents water passing through the aspirator 31 from being drawn into the container 25 where it would dilute the fluid.

Since the whole container 25 containing the fluid is rotated during the time that water from the hose 13 is passing through the apparatus and being discharged from the nozzles 34, the fluid within the container 25 is kept constantly agitated so that suspended materials do not settle out.

In the modification shown in Figure 3, the cap 50 is provided with a central vertical opening 51 in alignment with the opening in spindle 15. The upper end of this opening 51 is threaded to receive a Y connection 52 and discharge pipes 53 extend outward from this Y connection 52. The discharge pipes 53 are provided with aspirators indicated at 54 and nozzles 55 which extend through the openings 56 in the lid or cover 57. Suction pipes 58 extend from the aspirators 54 downward toward the bottom of the container 25. A ball check valve not shown and a pet cock 59 are provided in the suction pipe 58 as in the embodiment shown in Figures 1 and 2.

In the embodiment shown in Figure 3, the cover 57 and discharge aspirator and intake units are removed by turning the cover 57 relative to the container 25 and cap 50 until the Y connection 52 is unscrewed from the opening 51 in cap 50. The cover 51 carrying the discharge, aspirator and intake units may then be removed and fluid or solid material placed in the container 25. The container 25 may then be filled with the proper

amount of water through the opening 51 of cap 50 to form a solution of the desired concentration and the cover 57 carrying the discharge, aspirator and intake units replaced and the Y connection 52 screwed into the opening 51 of cap 50.

The operation and construction of the embodiment shown in Figure 3 is otherwise identical with the operation and construction of the modification shown in Figure 1.

It will be readily apparent that it is not necessary to place an aspirator and fluid suction pipe in each water discharge pipe. The aspirator and fluid suction pipe may be used in only one water discharge pipe and the other water discharge pipe or pipes may be ordinary pipes discharging plain water. It is also apparent that the various controls such as ball check 39, pet cock 40 and pet cock 49 may be omitted. I prefer to employ these controls and more accurate spraying is possible with them but my apparatus will function in the same manner if they are omitted.

It is also apparent that when the fluid intake is cut off by closing pet cocks 40 or 49 or both, my apparatus functions as an ordinary sprinkler.

From the foregoing it is apparent that I am able to attain the objects of my invention and provide a simple, efficient, effective apparatus for applying chemical fertilizers, weed or insect killers together with a water spray.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. Apparatus for spraying water soluble materials comprising a substantially vertical stationary hollow spindle having a fluid discharge port at its upper end, a hollow container for holding said material rotatably mounted on said spindle, a fluid discharge tube carried by said container, means for rotatably connecting said tube to said port, and an aspirator having a suction pipe in said tube, said pipe extending toward the bottom of said container.

2. Apparatus as defined in claim 1 including a discharge nozzle on said pipe outside said container, said nozzle being inclined at an angle to the axis of rotation of said container so that the reaction of fluid discharged from said nozzle tends to rotate said container.

3. Sprinkling apparatus comprising a substantially vertical hollow spindle having an exhaust port adjacent its upper end, means spaced from said upper end for connecting said spindle to a source of water under pressure, a cap rotatably mounted on the upper end of said spindle and having an opening therethrough communicating with said port, a container adapted to hold fluid to be mixed with the water spray, means for securing said container to said cap, a cover for said container, an exhaust pipe carried by said cover, means for securing said exhaust pipe to said cap at said opening, an aspirator in said pipe having a suction tube, said suction tube extending toward the bottom of said container.

4. Apparatus as defined in claim 3 including a

discharge nozzle on said pipe outside said container, said nozzle being inclined at an angle to the axis of rotation of said container so that the reaction of fluid discharged from said nozzle tends to rotate said container.

5. Sprinkling apparatus comprising a substantially hollow spindle having an exhaust port adjacent its upper end, a head rotatably mounted on the upper end of said spindle, said head having an opening therethrough communicating with said port, a fluid discharge tube carried by said head, a fluid container carried by said head, an aspirator in said tube and a pipe extending from said aspirator toward the bottom of said container.

6. Sprinkling apparatus comprising a substantially vertical stationary hollow spindle having a fluid discharge port at its upper end, a hollow member rotatably mounted on said spindle, a plurality of tubes projecting laterally from said member and disposed symmetrically with respect to the axis of rotation of said member, said tubes

being in communication with said opening through said member, a discharge nozzle at the outer end of each tube, an aspirator in one of said tubes, a fluid container carried by said member and a pipe extending from said aspirator toward the bottom of said container.
